CLAIM

The ornamental design for a wall console, as shown and described.

DESCRIPTION

FIG. 1 is a front and left side perspective view of a tip-out wall console with the shelf in closed position showing our new design;

FIG. 2 is a front elevational view thereof;

FIG. 3 is a side elevational view taken from the right of FIG. 1;

FIG. 4 is a top plan view thereof;

FIG. 5 is a rear elevational view thereof;

FIG. 6 is a bottom plan view thereof;

FIG. 7 is a front and left side perspective view with the shelf in open position.
